UNITED STATES PATENT OFFICE.

BERT MYER AND JOHN BROWN, OF ELKHART, KANSAS.

WRENCH.

1,421,536.

Specification of Letters Patent.

Patented July 4, 1922.

Application filed December 21, 1921. Serial No. 523,891.

To all whom it may concern:

Be it known that we, BERT MYER and JOHN BROWN, citizens of the United States, residing at Elkhart, in the county of Morton and State of Kansas, have invented certain new and useful Improvements in Wrenches, of which the following is a specification.

The present invention relates to wrenches and the object is to provide a nut wrench capable of being quickly adjusted and when adjusted having means whereby relatively movable jaws are locked effectively against accidental relative movement.

The preferred embodiment of the invention is illustrated in the accompanying drawings, wherein:

Figure 1 is a side elevation of the wrench, with the jaws in fixed relation,

Figure 2 is a plan view of the same,

Figure 3 is a view partly in section and showing the adjustable jaw released,

Figure 4 is a sectional view on the line 4-4 of Figure 3, with the jaw shank locked,

Figure 5 is a view similar to Figure 4, but showing the jaw shank free for adjustment.

In the disclosure, a stock 6 is employed having a handle 7 and a slightly offset terminal jaw 8 extending generally longitudinally of the handle and fixed with relation thereto.

The jaw portion is provided with a transverse opening 9 therethrough, in which is mounted the shank 10 of a movable jaw 11 that coacts with the jaw 8. In the opening 9 are located sets of oppositely disposed teeth 12, and the shank 10 is provided with oppositely disposed sets of teeth 13. The shank 40 is rotatable in the opening, and when so rotated the teeth 13 thereof move into and out of interfitting relation with the teeth 12 of the opening. When out of interfitting relation the jaw 11 is at right angles to the jaw 8, and when in interfitting relation the said jaw 11 is in coacting relation with said jaw 8. When the teeth are out of interlocked engagement the shank is freely slideable in the opening, as will be evident by reference to Figure 5.

When the movable jaw 11 is held by reason of the interfitting of the teeth 12 and 13, said shank and jaw may be fixed against rotation by means of fingers or wedges 14 that are carried by a swinging latch 15 pivoted, as shown at 16, to the stock 6. These fingers

or wedges 14 pass into the opening 9 on opposite sides of the shank, said sides being flat and smooth, as illustrated. The latch 15 is preferably provided with finger-pieces 17, 60 by means of which it can be conveniently swung.

With this structure, when it is desired to adjust the jaw 11 with relation to the jaw 8, the latch is swung to the position illustrated 65 in Figure 3, the shank 10 is turned until the teeth are free and the jaw is adjusted as desired. After such adjustment the jaw is turned until the teeth are in interfitting relation and the latch is then swung to its active position, whereby the movable jaw is effectively locked.

From the foregoing, it is thought that the construction, operation and many advantages of the herein described invention will 75 be apparent to those skilled in the art, without further description, and it will be understood that various changes in the size, shape, proportion and minor details of construction, may be resorted to without departing 80 from the spirit or sacrificing any of the advantages of the invention.

Having thus fully described our invention, what we claim as new, and desire to secure by Letters Patent, is:

1. A wrench comprising a stock having a guide opening provided with teeth, a jaw having a shank slideable and rotatable in the opening and provided with teeth that move into and out of interlocking engagement with the teeth of the stock on the rotation of the shank, and a holding device that enters the opening to prevent the rotation of the shank.

2. A wrench comprising a stock having a guide opening provided with teeth, a jaw having a shank slideable and rotatable in the opening and provided with teeth that move into and out of interlocking engagement with the teeth of the stock on the rotation 100 of the shank, and a holding latch pivoted on the stock and having a portion that enters the opening to prevent the rotation of the shank.

3. A wrench comprising a stock having a guide opening provided with teeth, a jaw having a shank slideable and rotatable in the opening and provided with teeth that move into and out of interlocking engagement with the teeth of the stock on the rotation 110 of the shank, and a holding latch pivoted on the stock and having portions that

enter the opening on opposite sides of the shank to prevent the rotation of the shank.

4. A wrench comprising a handle lever having an offset fixed terminal jaw member provided with a guide opening transverse to the handle and jaw, and a movable coacting jaw having an angularly disposed shank 5
slidable and rotatable in the opening, said shank and opening having sets of oppositely disposed teeth that move into and out of interfitting relation on the rotation of the shank, and 10 a latch pivoted on the handle and having

spaced wedges that enter the opening on opposite sides of the shank when the teeth are interfitted to prevent the shank from 15 being rotated.

In testimony whereof, we affix our signatures in the presence of two witnesses.

BERT MYER.
JOHN BROWN.

Witnesses:

WALTER SWAIN,
R. B. MAYS.
